UNITED STATES PATENT OFFICE.

MELVIN B. NEWCOMB, OF AKRON, OHIO, ASSIGNOR TO THE WELLMAN-SEAVIER-MORGAN COMPANY, OF CLEVELAND, OHIO, A CORPORATION OF OHIO.

VULCANIZING PRESS.

Application filed December 19, 1919. Serial No. 346,059.

To all whom it may concern:

Be it known that I, MELVIN B. NEWCOMB, a citizen of the United States, residing at Akron, in the county of Summit and State 5 of Ohio, have invented a certain new and useful Improvement in Vulcanizing Presses, of which the following is a full, clear, and exact description.

This invention relates to vulcanizing 10 presses, especially of the vertical type employed for the purpose of vulcanizing rubber tires, and the principal object of the invention is to provide between the lower hydraulic cylinder and the upper vulcanizing 15 chamber a supporting connection which is efficient and economical both in construction and in respect to the time and labor required to assemble the parts in their proper relationship.

20 The invention may be briefly summarized as consisting in certain novel details of construction, and combinations and arrangements of parts which will be described in the specification and set forth in the appended claims.

In the accompanying sheet of drawings, Fig. 1 is a vertical, sectional view through a vulcanizing press equipped with my invention, the upper and lower parts of the 30 structure being omitted; Fig. 2 is a sectional view on a reduced scale substantially along the line 2—2 of Fig. 1, looking in the direction indicated by the arrows; and Fig. 3 is a similar sectional view substantially along the line 3—3 of Fig. 1.

In the drawing, 10 represents the upper vulcanizing chamber which may be constructed in any suitable manner, as for example, by means of a shell at the top of 40 which will be a suitable removable cover, not shown, and which is secured at its lower end by rivets or the like 11, to a bottom casting 12. At a suitable distance below the casting 45 is a hydraulic cylinder 13 containing a plunger 14 which extends up through and has a bearing in the casting 12 of the vulcanizing chamber. At the top of the plunger 50 is a platen 15 on which the tire molds are adapted to be placed, and between which and the top cover of the chamber 10 they are compressed while the tires in the mold are being vulcanized.

To prevent leakage of steam downward

around the plunger, a packing gland 17 surrounding the plunger is secured by screws 55 or bolts 18 to the lower part of the casting 12, and to prevent leakage of water from the cylinder 13 around the plunger a packing gland 19 surrounds the plunger and is secured by screws or bolts 20 to the top of the 60 hydraulic cylinder 13.

To support the chamber and hydraulic cylinder in proper relationship, the following construction embodying the present invention is utilized.

At the top of the hydraulic cylinder is a ring 21, which rests on a suitable foundation, generally concrete, which ring has an opening through which the body of the hydraulic cylinder is extended, an external 70 flange 14^a at the top of the cylinder resting on an internal flange 21^a at the base of the ring. Preferably the upper part of the cylinder just beneath the flange 14^a has a close fit inside the flange 21^a. In this manner the 75 cylinder is well supported by the ring. This ring 21 has also lower and upper external horizontal flanges 21^b, (of which the internal flange 21^a is a continuation) and 21^c, suitably spaced apart and connected by ribs 80 21^d (see Fig. 3).

The supporting structure likewise includes an upper ring 22 which directly supports the vulcanizing chamber 10 by reason of the fact that the flange 12^a at the base of the casting 85 12 projects over and rests on the ring 22. Preferably the inner part of the ring 22 which accommodates the flange 12^a is reduced in thickness and is grooved to form a centering shoulder 22^a to accommodate a 90 similar shoulder formed on the lower face of the casting.

Additionally the supporting structure includes a plurality of vertical bolts or studs 95 23, in this case four in number, which bolts have reduced upper and lower ends which extend through the upper flange 21^c of the lower ring 21 and through the upper ring 22, and are provided with shoulders 23^a upon which the upper ring 22 rests, and 100 with lower shoulders 23^b which rest on the upper flange 21^c of the lower ring 21.

The structure is tightly clamped together by nuts 24 screwed onto the ends of the bolts, and by an upper split clamping ring 105 25 which is preferably in two parts, set onto

the reduced upper ends of the bolts before the upper nuts 24 are applied; and serving when the latter are tightened to clamp the flange 12^a of the casting tightly between 5 the ring 22 and the split clamping ring 25.

A rigid structure is thus provided, but nevertheless the parts can be very readily assembled or taken apart.

Suitable piping and valves, not shown, 10 will, of course, be utilized to control the supply of steam to the vulcanizing chamber and the supply and exhausting of water under suitable pressure to the cylinder.

While I have shown the preferred construction, I do not wish to be confined to the precise details shown, but aim in my claims to cover all modifications which do not involve a departure from the spirit and scope 15 of the invention in its broadest aspects.

Having described my invention, I claim:

1. In a vulcanizing press, an upper vulcanizing chamber having a flanged base, a hydraulic cylinder beneath the chamber in alignment therewith and having a plunger 25 extending through the base of the chamber, a separate ring at the top of the cylinder and constituting a support for the latter, a separate ring engaging the flanged base of the chamber and constituting a support 30 for the latter, and a plurality of spacing

and supporting bolts extending between said rings.

2. In a vulcanizing press, an upper vulcanizing chamber having a flanged base, a hydraulic cylinder beneath the chamber 35 and spaced a fixed distance therefrom, said cylinder being arranged co-axially with the chamber and having a plunger extending through the base of the latter, a supporting ring at the top of the cylinder and separate therefrom, a pair of supporting and clamping rings receiving the flanged base of the chamber, and clamping and positioning bolts extending between and secured to said rings.

3. In a vulcanizing press, the combination of a vulcanizing chamber having a bottom head; a hydraulic chamber in alignment with the vulcanizing chamber; a base on which the hydraulic chamber and vulcanizing chamber are mounted; a ram in the vulcanizing chamber; a piston extending from the ram through the head and base; and a series of posts each detachably and separately secured to the head and base 50 and supporting the vulcanizing chamber.

In testimony whereof, I hereunto affix my signature.

MELVIN B. NEWCOMB.
